Primary Examiner — Barbara Fox*Assistant Examiner* — Kristin E Reed(74) *Attorney, Agent, or Firm* — Steve O'Donnell(57) **CLAIM**

I claim the ornamental design for a track chair bracket, as shown and described.

DESCRIPTION

FIG. 1 is a front perspective view of a track chair bracket showing my new design;

FIG. 2 is a rear perspective view thereof;

FIG. 3 is front elevation view thereof;

FIG. 4 is a side elevation view thereof, the opposing side view being a mirror image; and,

FIG. 5 is a top plan view thereof.
